CIRCUIT INTERRUPTER

George N. Lemmon, Homewood, Ala., assignor to
 Southern States Equipment Corporation, Bir-
 mingham, Ala.

Application November 9, 1936, Serial No. 109,958
 Renewed July 15, 1939

9 Claims. (Cl. 200—116)

This invention relates to the type of circuit interrupter known as an expulsion fuse, in which a fusible link is placed inside an insulating tube which is open to the atmosphere at one or both ends, and which upon overload interrupts the circuit by the fusing of the link and the sudden explosive effect of the resultant arc inside the tube. It also relates to similar circuit interrupters in which the circuit is opened inside the tube by manual or electromagnetic means, instead of by thermal means.

Referring to the drawing, Fig. 1 shows a general view of an assembled unit embodying this invention; Figs. 2, 3 and 4 show in large scale details of the top latch in different positions; and Fig. 5 shows in perspective another position of these same parts.

The insulators 1, are supported by any suitable hanger 2, and in turn they support the forked bearing 3 and top fitting 4.

The latch hood 5 is pivoted at 6 and its travel in both directions is limited by the stop 7 on the fitting 4.

The tube 8 carries two trunnions 9 which are held by 3 and about which the tube pivots. The swing end of the tube carries the fitting 10 to which is pivoted the link 11 which in turn pivotally supports the latch 12. A fuse link 13 with- in the tube 8 completes the circuit between the line 14 and line 15. The screw 16 secures one end of the fuse link, and the screw 17 together with the plate 18 hold the button head 19 which is at the other end of the link 13. Tension on the link 13 prevents rotation of the latch 12 about its double pivot at 11.

When the tube is being closed in, the upper tip of the latch 12 engages with the tooth 5', thereby slightly rotating the hooded latch 5 about its pivot 6. The member 12 also pushes back the brush 24, and then 5 drops down aided by the spring 26, so that the projection 5' engages and holds 12 in closed position as shown in Fig. 1. When upon overload the fuse ruptures and tension on 12 is released, the latch 12 disengages from the tooth 5', and the tube 8 falls by gravity to the position shown by dotted lines in Fig. 1.

On such equipment a low-amperage fuse-link is often used, and it is desirable to prevent excessive strain upon this small link at all times. It is also advisable to protect moving joints from sleet which otherwise might prevent proper operation. The hood 5 has an internal pivotal mounting at 6 and the lower flared edges of 5 tend to divert rain or sleet away from the parts beneath. Also the latch 12 has an internal pivotal

mounting at 11, and thus further protection is given to this double-pivoted joint.

The wide end 20 of the latch 12 serves as a shield to keep rain out of the top opening of the tube 8, and further protection is given by the flange 21 on the fitting 10, and by the projecting end 23 of the tube 8. The flange 22 fits between 21 and 23 and gives additional protection against rain. When the fuse link has ruptured from overload, hot gases are expelled upward from the tube 8, and the interlocking arrangement of flanges retards hot gases from the tube from expanding towards the insulators, while allowing relatively free expansion away from the insulators. Since these hot gases are conductive, this is desirable.

The flanges also allow a slight transverse motion of the double pivot at 11. If the fused tube when put into service is slammed hard against the brush 24 and its stop 25, the parts assume the positions shown in Fig. 2, with the flange 22 bearing against the tube end 23, and taking the force of the blow away from the fuse link.

Then if the tube 8 is pulled or bounces outwardly, the motion of 11 allows the other side of 25 the flange 22 to be pressed against the flange 21, as shown in Fig. 3.

These members are usually castings, and their surfaces are slightly rough, due to the sand mold. When the flanges are pressed together there is considerable friction due to this roughness, and the rotation of the latch 12 about its pivots at 11 is thereby definitely retarded. This reduces the strain which is imposed on the link 13 under given conditions. Another factor in the reduction of strain on the link 13 is the fact that the tube 8 can move in or out somewhat while the latch 12 remains still; this softens the hammer-blow action of the tube 8. With a single pivot between 10 and 12 any counter-clockwise rotative strain on latch 12 would be borne entirely by the fuse link 13, with no diminution due to friction, and with all momentum of the tube 8 being applied to cause rotation of the latch 12.

Furthermore, when the fuse link 13 has been ruptured, as by overload, a very slight rotative motion of 12 allows the flange 22 to clear the flange 21, as in Fig. 4. Then as the tube 8 moves outwardly, the link 11 can drop downward with the latch 12, and so release the latch from 5', allowing the tube 8 to drop fully open.

There are various modifications which can be made from the details as here described without departing from the purpose and spirit of this invention.

I claim:

1. In a circuit interrupter, in combination, two insulated supports, a tubular container pivotally mounted upon one of said supports, a fusible conductor within the container, and a contact member connected to the swing end of the container by a double-pivotal mounting, and a second contact member supported by the second insulated support and engageable with the said first contact member.
2. In a circuit interrupter, two gap-spaced insulated terminals, an insulating tube with a flexible conductor therein movable into and out of circuit closing position between the said two terminals, a contact member to engage with one of said terminals and to hold the tube in closed-circuit position, said contact member being connected to the tube by a double jointed pivotal mounting.
3. In a circuit interrupter, two gap-spaced insulated terminals, an insulating tube with a flexible conductor therein movable into and out of circuit closing position between the said two terminals, a contact member to engage with one of said terminals and to hold the tube in closed-circuit position, said contact being connected to the tube by a movable link and two pivots.
4. In a circuit interrupter, two gap-spaced insulated terminals, an insulating tube with a flexible conductor therein movable into and out of circuit-closing position between the said two terminals, a metallic fitting near the upper end of the said tube from which the end of the tube projects, a latch member movably attached to the said fitting, said latch member and said fitting including interlocking barriers to modify the discharge of gases from the end of the tube.
5. In a circuit interrupter, two gap-spaced insulated terminals, an insulating tube with a flexible conductor therein completing the circuit across the said gap, one end of said tube being open for the discharge of gases, a movable cap adjacent the said open end of the tube, together with barriers adjacent the said cap and interlocked to retard the flow of any gas past the barriers.
6. In a circuit interrupter, two gap-spaced insulated terminals, an insulating tube with a flexible conductor therein completing the circuit across the said gap, one end of said tube being open for the discharge of gases, a movable cap adjacent the said end of the tube, together with means stationary with the tube and adjacent to the cap to direct the discharge of gases away from the said insulated terminals.
7. In a circuit interrupter, two gap-spaced insulated terminals, an insulating tube with a flexible conductor therein completing the circuit across the said gap, one end of said tube being open for the discharge of gases, a movable cap adjacent the said open end of the tube, together with a barrier stationary with the tube and a coordinated barrier on the cap, operable to modify the discharge of gases from the said tube.
8. In a circuit interrupter, a pivotally mounted tubular container, a fusible conductor within the container, a contact member mounted on the container by a double pivoted hinge, said contact member being also a protective shield for its own pivotal mounting.
9. In a circuit interrupter, two gap-spaced insulated terminals, an insulating tube with a flexible conductor therein movable into and out of circuit closing position between the said two terminals, a metallic fitting near the upper end of the said tube, a latch member movably attached to the said fitting and forming a protective shield for the end of the tube, said latch member and said fitting including coordinated means to modify the discharge of gases from the tube.
